UNITED STATES PATENT OFFICE.

FRANK A. KIRBY, OF DETROIT, MICHIGAN.

ATTACHMENT FOR DRILLING, BORING, AND SIMILAR MACHINES.

971,679.

Specification of Letters Patent.

Patented Oct. 4, 1910.

Application filed June 7, 1909. Serial No. 500,585.

To all whom it may concern:

Be it known that I, FRANK A. KIRBY, a citizen of the United States, residing at Detroit, in the county of Wayne and State of Michigan, have invented certain new and useful Improvements in Attachments for Drilling, Boring, and Similar Machines, of which the following is a specification.

This invention relates to an attachment for drilling, boring, and similar machines having a vertically reciprocable spindle or other movable member carrying the cutting tool and its object is to provide a simple and inexpensive device which may be readily attached to any ordinary machine of this character to limit the longitudinal movement of the spindle or other vertically reciprocable tool carrying member and which may be quickly adjusted to bring any one of a series of positive stops into operative position to accurately determine the depth to which the cutting tool shall go.

To this end the invention consists in providing a carrier for a series of stop members which carrier may be moved to quickly bring any one of the stops into position to engage and positively and accurately determine the length of movement of the tool carrying member, and in providing the device with certain new and useful features all as hereinafter more fully described reference being had to the accompanying drawings in which,

Figure 1 is a perspective view of a portion of an up-right drill showing the attachment embodying the invention in place thereon; Fig. 2 is a perspective view of the attachment drawn to a larger scale; Fig. 3 is a side elevation of the same; Fig. 4, a plan view; Fig. 5 a similar view of the collar; Fig. 6 is an enlarged sectional detail of one of the adjustable stop pins; and Fig. 7 is a cross section of the carrier showing the same upon a supporting bracket adapted to be secured directly to the machine head or frame.

As shown in Fig. 1, 1 is the base of an ordinary upright drilling machine from which rises the column 2 supporting a bracket carrying a suitable table 3, and upon which column a vertically movable head 4 is supported. 5 is a rotatable spindle to the lower end of which the cutting tool is attached and 6 is a sleeve vertically movable in the head and through which the spindle 5 extends. A rack 7 is provided upon the rear side of the sleeve 6 which rack is adapted to be engaged by a pinion upon a shaft 8 in the head.

The shaft 8 is actuated by a worm gear 9 engaging the worm 10 on the shaft 11 to which motion is imparted from a vertical shaft 12 by beveled gears 13. Motion is thus imparted to the sleeve 6 to move the same vertically through the head to automatically feed the spindle with its cutting tool downward. The shaft 11 is pivoted at its rear end so that it may fall at its forward end and disengage the worm 10 from the gear 9 and thus stop the transmitting of motion to the sleeve, and the downward feeding of the tool. A handle 14 is pivoted intermediate its ends to the head and a suitable connection 15 attached to its rear end connects the same with the forward end of the shaft 11 so that said shaft may be raised and held by the handle with its worm 10 in engagement with the pinion 9. All of the foregoing described parts are constructed and arranged to operate in an old and well-known manner, the drilling machine embodying said parts forming no part of this invention.

Pivoted to the forward side of the head 4 is a latch 16 having a bill or notch to engage the upper side of the handle 14 and hold the handle with the shaft 11 raised and the worm 10 engaged with its pinion to transmit motion to the sleeve 6 and feed the cutting tool to the work. This latch 16 is formed with a handle 17 by means of which it may be operated to disengage it from the handle 14 and upon the handle 17 is a bracket 18 to which is pivotally attached at its axis a circular carrier 19. This carrier may be a disk or it may be, as shown, a ring provided with a spider and axial hub through which its pivot pin for attaching it to the bracket, extends. In the upper side of the carrier is a series of spaced openings 20 to receive a series of stop pins 21 of different lengths. Each of the pins 21 is formed with a reduced lower end to engage the openings 20, said reduced portion forming a shoulder 22 on each pin to engage the upper surface of the carrier or ring 19. Each pin is also formed with a longitudinal screw-threaded bore to receive an adjusting screw 23 having a milled head, and a lock nut 24 on the screw locks the same in any position to which it may be adjusted. By adjusting the screw in or out of the bore the effective length of the pin may be varied. Each pin 21 is indicated by a number upon the periphery of the carrier diametrically opposite said pin and the

bracket 18 may, if desired, be extended, as shown, across the carrier, and provided with a pointer 25 so that when one of the indicating numbers 26 is brought in line with the pointer by turning the carrier, it will indicate that the pin represented by said number is in operative position.

A collar 27 is made in two parts pivotally connected at 28 and detachably secured together at the other side by a screw 29. This collar is clamped to the sleeve 6 by the drawing together of its parts by the screw 29, and said collar is prevented from shifting upon the sleeve by being provided with a rib 30 at its inner side to engage between the teeth of the rack 7 upon the sleeve 6. The collar is provided at its forward side with a downwardly projecting lug 31 which, when the sleeve is lowered, will come into contact with one of the pins 21 when the same is in operative position. The carrier 19 may be turned however, so that the lug will pass between two of the pins and thus moved downward to the limit of its stroke 25 or until the lug engages the carrier and actuates the latch to disengage the same from the handle 14 and stop the motion.

In Fig. 7 the carrier is shown pivotally attached to a bracket 32 which is adapted to be rigidly secured to the head 4 of the drill. This rigidly attached bracket is used upon a drill which is provided with a hand feed and when the sleeve 6 is fed down by the ordinary hand mechanism, the projection on the collar secured to the sleeve will engage one of the pins turned into alinement therewith and stop the feeding of the spindle.

In modern machine shop practice very accurate work is required and often a mechanic is given a job requiring the boring in succession of a number of holes of different depths. As these machines are ordinarily constructed it is necessary for the mechanic to set the machine for each hole and this takes a great deal of time especially where very accurate work is required, and the operator is liable to make mistakes. By providing the machine with the attachment described, the operator will place in the carrier, pins of such a length that the latch will be operated and the feeding stopped when the tool has reached exactly the proper depth each pin corresponding to the depth of hole required. These pins form positive stops which will determine the depth of hole each time without a variation, and being carried upon the rotatable table or carrier 19 any one of them may be quickly brought into operative position. For extreme accuracy the adjusting screw 23 is provided in each pin, this screw being adjusted to compensate for wear of the cutting tool etc., and to accurately determine the length of the pin. The collar 27 may be quickly adjusted upon the sleeve to adjust the stroke

of said sleeve and when so adjusted it is rigidly held against movement thereon by being firmly clamped thereto, and also by the engagement of its rib 30 with the rack 7.

While I have illustrated this invention as applied to an upright drill, I do not wish to limit myself to such application as it is apparent that the attachment may be used upon other types of machines and machines for other purposes, and I do not wish to confine myself to the specific construction as it is obvious that various changes within the scope of the appended claims may be made in the construction to suit the machine to which it is applied without departing from the spirit of the invention.

Having thus fully described my invention what I claim is:

1. The combination in a machine having a vertically movable spindle, means for moving the spindle and means adapted when operated to throw the moving means out of gear, of a stop on the throw-out means and a collar adjustably and detachably secured around the spindle and adapted to co-act with the stop to operate the throw-out means when the spindle reaches a predetermined point.

2. The combination in a machine having a vertically movable spindle, means for moving the spindle and means adapted when operated to throw the moving means out of gear, of a stop on the throw-out means and a collar around the spindle having two complementary members pivotally-connected at one end and means detachably securing the other ends, the collar being adapted to co-act with the stop to operate the throw-out means when the spindle reaches a predetermined point.

3. The combination in a machine having a vertically movable spindle, a rack on the spindle, means for moving the spindle and means adapted when operated to throw the moving means out of gear, of a stop on the throw-out means and a collar adjustably and detachably secured around the spindle in interlocked relation with the rack and adapted to co-act with the stop to operate the throw-out means when the spindle reaches a predetermined point.

4. The combination in a machine having a vertically movable spindle, a rack on the spindle, means engaging the rack for moving the spindle and means adapted when operated to throw the moving means out of gear, of a stop on the throw-out means, a collar adjustably and detachably secured around the spindle, and a rib on the collar detachably interlocking with the rack, the collar being adapted to co-act with the stop to operate the throw-out means when the spindle reaches a predetermined point.

5. The combination with a machine having a vertically movable spindle, a rack on

the spindle, means engaging the rack for moving the spindle, and means adapted when operated to throw the moving means out of gear, of a stop on the throw-out 5 means, a collar adjustably and detachably secured around the spindle in engagement with the said rack, and a lug on the collar adapted to coact with the stop to operate the throw-out means when the spindle reaches 10 a predetermined point.

6. The combination with a machine having a vertically movable spindle, means for moving said spindle, and means adapted when operated to throw the moving means 15 out of gear, of a vertically adjustable stop

on the throw-out means, a collar on the spindle adjustable longitudinally thereof, and a lug on the collar adapted to coact with the stop to operate the throw-out means when the spindle reaches a predetermined point, 20 the stop being movable in a plane transversely of the axis of the spindle out of the path of travel of the lug.

In testimony whereof I affix my signature in presence of two witnesses.

FRANK A. KIRBY.
